US0D1013007S

(12) **United States Design Patent** (10) **Patent No.:** **US D1,013,007 S**
(45) **Date of Patent:** **** Jan. 30, 2024**

(54) **FURNITURE ACCESSORY WITH CAMERAS**

(71) Applicant: **Magic Leap, Inc.**, Plantation, FL (US)

(72) Inventors: **Shigeru Natsume**, Weston, FL (US);
Sebastian Gonzalo Arrieta Gunther,
Fort Lauderdale, FL (US); **Haney Awad**, Fort Lauderdale, FL (US);
Bryson John Green Mercer, Miami, FL (US)

(73) Assignee: **Magic Leap, Inc.**, Plantation, FL (US)

(**) Term: **15 Years**

(21) Appl. No.: **29/717,260**

(22) Filed: **Dec. 16, 2019**

(51) LOC (14) Cl. **16-01**

(52) U.S. Cl.

USPC **D16/200**

(58) **Field of Classification Search**

USPC D16/200, 207–208, 211–215, 217–219,

D16/245; D10/46, 70, 104.1, 106.6;

D14/203.1, 204, 203.8, 209.1, 317, 474,

D14/496; D26/3, 36, 37, 42, 43, 46, 63,

D26/69, 79, 93

CPC G03B 17/00; G03B 17/48; G03B 2217/56;

G03B 2217/565
